US00D932484S

(12) **United States Design Patent** (10) **Patent No.:** **US D932,484 S**
(45) **Date of Patent:** **** Oct. 5, 2021**

(54) **LAPTOP**

(71) Applicant: **NVIDIA Corporation**, San Jose, CA (US)

(72) Inventors: **Yongju Kwak**, San Jose, CA (US); **Boris Landwehr**, Thousand Oaks, CA (US); **Pei-Lin Lo**, Taipei (TW); **Andrew Robert Bell**, San Francisco, CA (US); **Gabriele Gorla**, Santa Clara, CA (US)

(73) Assignee: **NVIDIA Corporation**, San Jose, CA (US)

(**) Term: **15 Years**

(21) Appl. No.: **29/699,332**

(22) Filed: **Jul. 24, 2019**

(51) LOC (13) Cl. **14-02**

(52) U.S. Cl.

USPC **D14/315**

(58) **Field of Classification Search**

USPC D14/203.4, 247, 315-327, 331, 345-346, D14/371-372, 376-377, 391-399, 401, D14/429, 434, 440, 455-457, 477, 507, D14/441, 448-451, 501, 203.8, 302, 336, D14/339; D21/324, 409, 512, 515; D24/158-159, 186

CPC B41J 3/36; G06F 1/1616; G06F 1/1643
